UNITED STATES PATENT OFFICE.

JOHN BERNARD MORRIS, OF PHILADELPHIA, PENNSYLVANIA.

COMBINATION-LOCK PACKING-BOX AND SAVINGS-BANK.

SPECIFICATION forming part of Letters Patent No. 472,136, dated April 5, 1892.

Application filed June 10, 1891. Serial No. 395,751. (No model.)

To all whom it may concern:

Be it known that I, JOHN BERNARD MORRIS, a citizen of the United States, and a resident of Philadelphia, Pennsylvania, have invented 5 certain Improvements in a Combination-Lock Packing-Box and Savings-Bank, of which the following is a specification.

My invention consists of a packing-box for candies, stationery, or other similar goods 10 which can afterward be used as a toy money-bank.

In the accompanying drawings, Figure 1 is a perspective view showing the box closed. Fig. 2 is a view showing the lid partially raised 15 and a portion of the locking-tongue exposed. Fig. 3 is a sectional view showing the tongue locked to the box. Fig. 4 is a view showing the tongue unlocked. Fig. 5 is an enlarged sectional view on the line 1 2, Fig. 3. Figs. 20 6, 7, and 8 are detached perspective views of portions of the box; and Figs. 9 and 10 are views of modifications.

A is the body of the box, made, preferably, of pasteboard, but may be made of any other 25 suitable material, depending upon the use to which the box is put.

The box is so folded in the present instance as to form at one end a lid B. The opposite end of the box is also preferably provided 30 with a lid, which can be used when the goods are packed in the box. This lid can be sealed when the box is in use as a toy money-bank, and the lid B is then used as a lid of the bank. A suitable slit can be made in any portion of 35 the bank to admit the money. Secured to the lid B is a tongue D, extending into a slot b, as clearly shown in Fig. 5, formed by the outer surface a of the box and an inner lining a', Fig. 6, filling-pieces a², Fig. 7, being inserted between the box and lining. These filling-pieces 40 a² are recessed at c on each side of the slot b to receive the locking-disks. Pivoted to the tongue D is a series of disks E, having their sides cut away, as shown in Fig. 4, so that 45 when the tongue is inserted in the slot b it can pass in between the filling-pieces a² and into the position required.

In the outer wall a of the box is a series of 50 openings i opposite each disk when in position, as in Fig. 4, so that a child by using a pin or similar implement can turn the disks through the slot until they assume the position shown

in Fig. 3, thus locking the tongue and lid to the box. I have shown three disks in the present instance; but two may be used, or even 55 one may be used, without departing from my invention.

In Fig. 2 I have shown a single tongue and the disks arranged in line one under another.

It will be seen that after the box has been 60 used for confectionery or other goods the lid can be sealed and an opening made for the insertion of money and the box used as a money-bank.

I prefer to letter each of the disks, as shown, 65 in any suitable manner. For instance, in Fig. 1 I have shown three disks, the letters thereon being so arranged that a certain word will first have to be spelled by moving the disks—such, for instance, as the word “cat”— 70 the letters being so arranged that when the “c” on the first disk is opposite its opening the disk is free of the recesses c, the second disk is free when “a” is opposite its opening, and when “t” is opposite the opening the 75 third disk is free and the tongue can then be readily removed, the full word being spelled.

The box may be made of metal or other material without departing from my invention.

It will be understood that the undercut 80 slideway may be in the lid, as shown in Fig. 9, and the tongue secured to the body portion of the box. Two tongues may also be used, as shown, without departing from my invention. 85

In Fig. 10 I have shown the disks pivoted to the box and the tongue D recessed to receive the disks.

It will also be understood that figures or emblems may be used instead of letters in 90 marking the disks.

I claim as my invention—

1. The combination, in a box used as a savings-bank having a body portion and a lid, a tongue on either the body or the lid, and a 95 groove in the opposite portion adapted to receive the tongue with locking-disks for locking the tongue in the groove, substantially as and for the purpose described.

2. The combination, in a box used as a savings-bank having a body portion and a lid, a tongue on either the body or the lid, having one or more disks swiveled thereon, and an undercut groove in the opposite portion adapt- 100

ed to receive the tongue, substantially as and for the purpose described.

3. In a money-box, the body portion, the lid, a tongue on said lid, one or more disks on said tongue, said tongue and disk being adapted to a slot in the side of the box, with an opening in the box opposite the disk, substantially as and for the purpose set forth.

4. The combination of the box, a lid therefor, a tongue on said lid having one or more disks swiveled thereon and said disks being eccentric in form, the disks and tongue adapted to a slideway in the box, with openings in the front portion of the box, whereby the disks may be manipulated so that the lid can be opened, substantially as described.

5. The combination of the box, the lid, the tongue extending from said lid, one or more eccentric disks on the tongue, said disks having letters marked thereon, an opening in the box in front of the row of letters of each disk, through which the disk can be turned, with a

backing-plate and undercut filling-pieces forming a slideway for the tongue, whereby when the disks are turned into the undercut portion the tongue will be locked to the box, substantially as described.

6. The combination of the pasteboard box cut, substantially as described, to form a lid, a filling-block a^2 , having undercut edges, pasteboard lining-piece a' , forming with the side of the box an undercut way, a tongue secured to the lid, disks pivoted to the tongue, said disks being eccentric in form and having letters marked thereon, with openings in the box, substantially as described.

In testimony whereof I have signed my name to this specification in the presence of two subscribing witnesses.

JOHN BERNARD MORRIS.
